UNITED STATES PATENT OFFICE.

SIDNEY L. MENGE, OF NEW ORLEANS, LOUISIANA.

LOW-LIFT PUMP.

Application filed March 9, 1928. Serial No. 260,527.

My present invention relates to improvements in low lift pumps intended for delivering large bodies of water through a short lift, and especially adapted for pumps for 5 draining or irrigating fields.

My present invention consists in an improvement on the well-known Menge pump, widely used for irrigation and drainage purposes in the South, and which is illustrated 10 and described in a number of patents, amongst which are:

Reissued Letters Patent to Joseph Menge, No. 11,214, dated December 29, 1891; also Letters Patent to Joseph Menge, No. 471,486, 15 granted March 22, 1892; also Letters Patent to Sidney L. Menge, Nos. 950,398, granted February 22, 1910; and 1,630,130, granted May 24, 1927.

In this type of pump, there is a free passage for the water, which is pushed through 20 without being subjected to any material pressure, thereby differing from snail or other force pumps.

My present invention will be more fully 25 understood after reference to the accompanying drawings, in which like parts are indicated by similar reference symbols throughout the several views, and in which

Figure 1 shows a sectional elevation 30 through the center of the pump casing, in which a rectangular wooden box is used, the propeller and pump shaft being shown in elevation.

Figure 2 shows a section along the line 35 2-2 of Figure 1, looking down.

Figure 3 shows a modification, in which the pump casing is made of metal and substantially cylindrical in form, and

Figure 4 shows an inverted plan view of 40 the construction shown in Figure 3.

Referring first to Figures 1 and 2, A represents the pump casing preferably having the closed bottom A', so that the casing may be set up on the bottom of the ditch or the drain. 45 Above the bottom, inlet openings A⁰ are provided for the influx of water. At the corners of the box are provided vertical beams A², to which the sides of the pump casing are attached. The top of the casing is open, as 50 shown in Figure 1, and carries the cross beams A³ and A⁴, as shown in said figure.

One side of the pump casing is provided 55 with an outlet passage above the delivery trough B, which may be made of wood, and should be suitably braced, as by the braces C. D and D' represent two shelves, which are

mounted above and below the housing E, and which shelves are provided with a circular opening in the center thereof to register with the opening through the housing aforesaid, 60 as will be hereinafter described.

This housing E is provided with a tapered bore e' in the form of a frustum of an inverted cone, the elements of said cone having a very slight inclination, and below and 65 above this tapered bore, the housing is flared outward, as at e and e², so as to give a free passage for the water, as it is pushed upward through the pump.

The purpose of the entering and leaving 70 cones e and e² is to gradually increase the velocity of the flow of the water from the entrance velocity at A⁰ to that which the water will attain in the propeller chamber e'. The purpose of the inverted cone e² is to 75 gradually reduce this velocity to a much lower velocity in the discharge chamber; thereby causing an increase in efficiency. These cones e, e' and e² also have the additional purpose of reducing the whirl in the 80 water, caused by the rapidly rotating screw propeller.

Below the shelf D, I provide a cross piece F, preferably triangular in cross section, to facilitate the flow of water, carrying the 85 bearing G for the lower end of the propeller shaft H, to which shaft the hub I of the propeller is secured, said propeller having blades I', which blades are of a suitable pitch to lift the water to the desired height. 90

Above the shelf D' may be provided a cross piece F' also preferably triangular in cross section, carrying the journal bearing G' for the pump shaft, and above the beam A², I provide an anti-friction bearing J, preferably a ball bearing, having balls j on which the base of the nut K rests.

This ball bearing and nut form a suspension bearing on which the weight of the propeller and its shaft is normally suspended, and when in use, this bearing also serves as a thrust bearing to resist the downward pressure of the water as it is forced upward.

This nut is adjustably mounted on the 105 screw thread h on the upper end of the shaft, and if desired, a lock nut K' may also be used. The propeller shaft is adjusted vertically by screwing up or easing up on this nut K, so that the propeller blades will just clear the conical bore e', and as the tips wear, as will occur due to the presence of sand, grit or the 110

like in the water as it goes upward, by easing up on this nut K, the shaft A is permitted to descend slightly, and the tips of the propeller blades will just clear the lower portion of the bore where the calibre is somewhat less.

5 By this arrangement, the tips of the propeller blades may be conveniently adjusted, so as not to touch, but just clear the adjacent portion of the bore of the housing E.

10 The propeller shaft may be driven in any convenient way, as by means of a pulley, or by direct connection with a motor, not shown.

While I have shown, in Figures 1 and 2, a circular housing E in a rectangular pump casing, I recognize that a rectangular casing has its disadvantages with regard to the free circulation upward of the water; but it has its advantages, owing to cheapness of construction and facility with which the parts 20 may be assembled and used.

But in order to secure a somewhat increased efficiency of the pump, the pump casing may be made free from angles or of a substantially cylindrical form such as is shown in Figures 25 3 and 4, in which the casing is made of two parts, the lower part M being flared at the bottom, as at m, and provided with a flange m' at the top. In this bottom section, I provide the housing E', having the tapered bore 30 e' and the conical surfaces e and e², as already described with reference to Figures 1 and 2.

On top of this section M, I provide a spider N, having its ends n resting on the flange m' at the upper end of the section M. The upper 35 section M' of the pump casing has a delivery passage M⁰ between the curved guide surfaces m³ and m⁴. Above the outlet passage, the pump casing may be continued in the cylindrical form, as at M⁵, if desired.

40 The propeller hub I, carrying the blades I', is secured on the shaft H', which passes through the journal bearing n' and m⁵ and also through the anti-friction bearing j, which is supported on the head O of the pump casing. The nut K rests on the ball j, and this

50 nut forms a suspension and thrust bearing for the propeller shaft. This nut may be adjusted so that the tips of the blades I' may be set at the desired distance from the bore e', as hereinbefore described.

In addition to the nut K, I may provide a lock nut K', if desired.

55 The propeller shaft may be driven in any suitable way, as by a pulley, gear or other arrangement carried by the extension shaft H² connected by the coupling members h' and h² to the propeller shaft H'. In this form of pump casing having the flared bottom M, obviously this must be raised clear of the ground, and for this reason, I provide supporting 60 brackets P, which may rest on any suitable frame work, not shown.

65 While I have illustrated and described two embodiments of the invention in the preferred forms, it will be obvious that various changes could be made in the construction, combination and arrangement of parts, which could be used without departing from the spirit of my invention, and I do not mean to limit the invention to such details, except as particularly 70 pointed out in the claim.

Having thus described my invention, what I claim and desire to secure by Letters Patent of the United States is:—

75 A propeller pump comprising a casing provided with a lower or suction chamber and an upper or delivery chamber, with means for admitting water to the lower chamber, and for carrying it off from the upper chamber, a partition mounted between said chambers and provided with a bore in the form of the frustum of a slightly tapered inverted cone, said partition being provided with frusto conoidal faces flaring outwards above and below said bore, a shaft journalled in said casing concentric with said bore, and a screw propeller mounted on said shaft and having the tips of its blades in close proximity to said bore. 85

SIDNEY LAWRENCE MENGE.
